RESPIRATOR

Nathan Schwartz, New York, N. Y., assignor to
Hygeia Filtering Corporation, New York, N. Y.

Application May 13, 1939, Serial No. 273,439

8 Claims. (Cl. 128—146)

This invention relates to filter type respirators applied to cover the nose and mouth of the wearer for the purpose of protection against dust fumes and gases and is a modification of my copending applications, Serial No. 122,169 of January 25, 1937, Serial No. 124,851 of February 9, 1937, Serial No. 116,456 of Dec. 18, 1936, (now Patent No. 2,160,317, dated May 30, 1939,) Serial No. 222,139 of July 30, 1938, and Serial No. 112,646 of Nov. 25, 1936.

The object of this invention is to provide a light, comfortable and efficient respirator.

Another object is to provide a comfort air pad at the bridge of the nose.

Another object is to place the head band connection in a manner to automatically provide a leak proof and comfortable juncture between the face of the wearer and the face piece of the respirator.

Another object is to locate the exhalation valve conveniently and provide protection thereto.

Another object is to provide a large filter pad pleated and folded in a manner whereby it is easily manipulated and inserted in a casing which casing is adjacent to the face piece of the respirator.

With these and other objects in view reference is had to the following description and the accompanying drawings in which there is exhibited one example or embodiment of the invention, while the claims describe the actual scope of the same.

In the drawings:

Figure 1 illustrates the respirator in section and in applied position.

Figure 2 is a top view showing head band connection to the casing, and the valve screen positioned between the casing and face piece.

Figure 3 is a perspective of nose flange and the two lateral slits.

Figure 4 is the same as 3 showing the inward fold of the central part of flange.

Figure 5 is a section on line 5—5 of Figure 1, illustrating the valve and valve screen.

Figure 6 is perspective of valve screen.

Figure 7 is perspective of the filter pad and the corrugated filter spacer.

Figure 8 is the filter pad folded and partly broken to show the corrugated spacer.

Figure 9 is the same as Figure 8 with the apex of the pad forming an additional lateral fold.

Figure 10 is the same as 9 with the base of the pad opened and ready for insertion into casing.

Figure 11 shows the casing partly broken with filter pad emplaced.

Reference is made herein to the following drawings: Figure 12 is a perspective of foraminous lid for casing. Figure 13 is a perspective of marginal portion of casing showing the slit and tine protrusion therein. Referring to the drawings by characters of reference, A designates the face piece of the respirator, B the filter unit, C the valve screen, D the valve, and E the head bands. The face piece A is a substantially hollow cup shaped molded semi-flexible body, preferably of rubber material. It has a vertical nose covering portion 10 and a set back below the nose line 11. The set back is formed by a horizontal nose covering portion 12, a mouth covering portion 13, and 15 a chin covering portion 14. A flap valve D is located at the mouth covering portion, and the filter unit B is located and attached at the chin covering portion.

The face piece A has an inturned flange 15 at the nasal area which flange is slit in two places, at the sides of the bridge area. A central tongue 16 is thus formed which is folded toward the nose covering portion 10 and attached thereto by means of cement. The attachment of the tongue 16 to the nose covering portion 10 is made at the edges of said tongue 16 and therefore an air space 11 is thereby formed. It is to be noted that the tongue 16 has lateral sides 18 and an aperture 19 is formed thereat to permit inlet and outlet of air to and from the air space 17. It is apparent that thereby ease and comfort are provided for the bridge of the nose. The tongue 16 is to be rather thin so as to permit a wide range of resilience to accommodate any shape of nose. The slits are to be made in such a manner that they come to within about one eighth of an inch of the outer margin 20, and thereby the fold formation thereat permits a leak proof juncture. The flanges 15 are to be substantially thick to provide a firm and leak proof juncture at the sides of the nose. At the cheek of the wearer the margin of the face piece is preferably arranged for flange contact as shown in my copending application 112,646. It is to be noted that the nasal flange 15 gradually diminishes and flattens in merging with the cheek part adjacent the nose and face juncture. The fusion is clearly shown in Figures 2, 3 and 4 of the drawings. The said arrangement provides comfort at the parts and also makes the contact joint of the face piece of the respirator and the face of the wearer at the said part leak proof, and therefore when the respirator is in applied

position as will be described below. Figure 12 is a perspective of foraminous lid for casing. Figure 13 is a perspective of marginal portion of casing showing the slit and tine protrusion therein. Referring to the drawings by characters of reference, A designates the face piece of the respirator, B the filter unit, C the valve screen, D the valve, and E the head bands. The face piece A is a substantially hollow cup shaped molded semi-flexible body, preferably of rubber material. It has a vertical nose covering portion 10 and a set back below the nose line 11. The set back is formed by a horizontal nose covering portion 12, a mouth covering portion 13, and 15 a chin covering portion 14. A flap valve D is located at the mouth covering portion, and the filter unit B is located and attached at the chin covering portion.

The face piece A has an inturned flange 15 at the nasal area which flange is slit in two places, at the sides of the bridge area. A central tongue 16 is thus formed which is folded toward the nose covering portion 10 and attached thereto by means of cement. The attachment of the tongue 16 to the nose covering portion 10 is made at the edges of said tongue 16 and therefore an air space 11 is thereby formed. It is to be noted that the tongue 16 has lateral sides 18 and an aperture 19 is formed thereat to permit inlet and outlet of air to and from the air space 17. It is apparent that thereby ease and comfort are provided for the bridge of the nose. The tongue 16 is to be rather thin so as to permit a wide range of resilience to accommodate any shape of nose. The slits are to be made in such a manner that they come to within about one eighth of an inch of the outer margin 20, and thereby the fold formation thereat permits a leak proof juncture. The flanges 15 are to be substantially thick to provide a firm and leak proof juncture at the sides of the nose. At the cheek of the wearer the margin of the face piece is preferably arranged for flange contact as shown in my copending application 112,646. It is to be noted that the nasal flange 15 gradually diminishes and flattens in merging with the cheek part adjacent the nose and face juncture. The fusion is clearly shown in Figures 2, 3 and 4 of the drawings. The said arrangement provides comfort at the parts and also makes the contact joint of the face piece of the respirator and the face of the wearer at the said part leak proof, and therefore when the respirator is in applied

position its contact at the nasal area is comfortable and leak proof.

The valve D is formed at the mouth covering portion 13. The mouth covering portion 13 is flat and has a plurality of perforations 21. Two pins 22 are disposed at the upper lateral portions, one on either side. These pins 22 may be integral with the wall 13 or may be attached thereto by being inserted or riveted thereto. A thin rubber flap 23 having holes 24, which holes register with the pins 22, is emplaced in covering relation to the wall 13 with the pins 22 being inserted in the holes 24. During exhalation the flap 23 is blown forward and thereby an opening 15 is formed for easy escape of exhaled air. The valve D is protected from outer deleterious influences by a screen, the construction of which will be given later.

The filter unit B is preferably constructed of light metal such as aluminum. It has a casing 25, which casing has a rear wall 26 and a peripheral rim 27 and an inturned flange 28. The rear wall 26 has an aperture 29. The inturned flange 28 has several slits 30 and in several places 25 it protrudes outwardly to form tines 31 for the purpose of impinging the edges of the filter pad.

The filter pad 32 is preferably circular to fit into a similar shaped casing but may be oval or square to fit similar shaped casings. A corrugated and perforated spacer 33 is placed centrally on the filter pad and a median fold is made with the edges in coaptation position. The median fold reduces the pad to 180 degrees. Another median fold is made reducing the pad to 90 degrees, as shown in Figure 8. The pad is now wedge shaped having a base 34 and an apex 35. The apex 35 is folded towards the base 34, as shown in Figure 9, and the base leaves are separated, three leaves on one side 40 and one leaf on the opposite side thereby forming a circle as shown in Figure 10, and it thus ready to be inserted into casing.

Figure 11 shows the marginal portion of the casing 25 and the edges of the filter pad base 34 45 spread and adjusted at the outer side of the flange 28. The figure is illustrated in parts broken to show the corrugated spacer 33 and also the slits 30 and the tines 31.

Figure 12 shows the foraminous lid member 50 36. This lid has a marginal flange 37 which is disposed at about right angles to its plane.

The edges of the filter pad are mounted at the outer portion of the inturned flange 28, and the lid 36 is emplaced at the inner side of the 55 filter pad edges and thereby the said edges are secured to the said flange 28. The slits 30 permit a yield in the said flange 28, and the protrusions or tines 31 impinge at the said filter pad edges and firmly secure same at the joint 60 formed thereto. It is to be noted that the edges of the flange 37 are directed inwardly. A central protrusion 38 is provided for the lid 36 which is for the purpose of thumb hold in order to permit easy replacement of said lid 36.

65 The valve screen C is preferably of light aluminum material and has a body portion 39 which is perforated to allow free outward passage of exhaled air. It has an anterior convexity to form an enclosure for the valve D. At its upper 70 and central portion it has a hook extension 40. The said hook 40 is inserted in an aperture 41. The said aperture 41 is formed in a lug extension 42 at the lower part of the nose covering 10.

The filter unit is attached to the face piece as 75 follows: the rear wall 26 of the casing has an

aperture 29. The chin covering wall 14 of the face piece has a similar aperture 43 and it is located in registering position with aperture 29. An eyelet 44 is inserted and passed through both apertures and both edges of the eyelet are everted to form outward extending flanges, which flanges impinge upon the walls 26 and 14 and thereby clamp them together, thereby a leak proof joint is formed thereto.

At the rear side of wall 26, two metal strips 10 45 are attached. These metal strips are positioned lateral to the eyelet juncture of the face piece and filter unit. These strips 45 each have a flange 46 at one end, which are for the purpose of attachment by means of rivets 47 to the casting rear wall 26. At the opposite ends the said strips have hook formations 48. The head bands 15 E have metal slides 49 attached thereto at one extremity. These slides have holes which are slipped over the hooks 48. The said head bands 20 E have hook and slide respectively at the rear extremity for connecting one to the other and thereby fastening the respirator to the face of the wearer.

The face piece A has lateral protrusions 49'. The positioning of the head band attachment is so arranged that the head bands lie over the protrusions 49' when in position, the pulling of the said head bands causes a compression on the said protrusions 49' and thereby the face piece 30 at its lateral area is tightly drawn toward the face. As this pulling and compression occurs the flanges 15 of the face piece adjust themselves in the lateral nasal depression area and a tight leak proof juncture is formed thereto.

It is to be noted that several advantages are gained by using a cone shaped filter pad made as herein described. First, a large filter surface area is maintained in a small casing or filter housing. Second, folding of the pad is very simple. It requires no sewing or cementing at the folds or edges. Third, a perforated and corrugated spacer inserted at the hollow apex portion of the pad is useful for maintaining the large surface area.

Other advantages to be noted are as follows: The nose area is made comfortable and also leak proof by the flange and pad arrangement thereat. An improper nose engaging respirator causes irritation to the wearer and he will wear the 50 respirator hanging at his neck for relief, and expose himself to the dangers of the dust or fumes rather than forego the irritation of the respirator. Also the displaceable foraminous screen element for the valve provides for longer 55 life to the said valve. Also the lateral face piece protrusion provides an automatic means to secure in a leak proof manner the engagement of the said face piece and the face of the wearer. Also the displaceable foraminous screen 60 element for the filter pad aids in maintaining the said pad in good repair and its edges aid in securing same at the inlet port of the filter housing.

Having thus described my invention, I claim 65 as new and desire to secure by Letters Patent as follows:

1. In a respirator, a face piece of molded elastic material adapted to engage the face of the wearer and being padded at the bridge of the 70 nose area for comfort to the nose thereat, and the said face piece having a set back portion below the nose line and having a screened exhalation valve located at the said set back portion, a filter unit, comprising a casing having 75

removably mounted therein a filter pad which pad has a plurality of folds, and the said casing communicating with the said face piece and being located adjacent thereto, and the said face piece 5 having protrusions located sidewise in the lateral nasal area, a pair of head bands being attached laterally to the rear of the said casing in the lateral area of the face piece and arranged to press upon the said protrusions and thereby provide a leak proof connection between the face of 10 the wearer and the face piece of the respirator.

2. In a respirator, a face piece adapted to engage the face of the wearer and having a flexible inturned flange at the nasal area and the said flange having two slits located to correspond to 15 the sides of the bridge of the nose, and the portion of the flange between the said slits folded and cemented at its edges to the inner adjacent part of the face piece and thereby forming a pad 20 thereat to provide comfort to the bridge of the nose substantially as described.

3. A separator for filter type respirators including a casing having an inlet port with filter means comprising a filter pad with a plurality of 25 folds and an aperture, a marginal seat provided at the said inlet port, and a foraminous screen element, the said pad being enclosed within the said casing and the aperture thereof made to register with the said inlet port in a manner 30 whereby the edges of the said pad are impinging- 35 ly held between the said seat and the periphery of said element, and the said element is in outer protective relation to the said pad.

4. A separator for filter type respirators including a casing having an inlet port with filter means comprising a hollow filter pad formed by 40 means of a plurality of folds, the said pad having an aperture registering with the said inlet port, and a screen foraminous element, the said pad being removably mounted within the said casing and the said element is disposed in outer con- 45 fronting relation to the said pad, and thereby protects the same from deleterious influences.

5. In a respirator, a face piece adapted to en-

gage the face of the wearer in covering relation to the nose and mouth, and having a set back portion below the nose line, an exhalation valve located at the said set back portion, a foraminous screen element for the said valve and means to 5 removably mount the said element in outer protective relation to the said valve, whereby repair and replacement of said valve is made easy.

6. In a respirator, a face piece adapted to engage the face of the wearer in covering relation 10 to the nose and mouth, an exhalation valve being connected to the said face piece in the region of the nose and mouth, an apertured lug located adjacent the nose covering portion, and a foraminous screen element removably mounted in outer 15 confronting relation to the said valve by having a hook attachment which hook is inserted in the said apertured lug, and thereby the said element protects the said valve from outer deleterious influences and also permits easy access thereto for repair and replacement purposes.

7. A separator for filter type respirators including a substantially cup shaped casing having an inlet port with filter means comprising a marginal seat, a substantially cup shaped filter pad, and a screen foraminous element having a marginal flange, the said pad being removably mounted within the said casing by having its edges impingly held between the said seat and the said flange, and the said element being disposed in outer protective relation to the said pad.

8. A separator for filter type respirators including a casing having an inlet port with filter means comprising a marginal seat, a hollow and substantially cupped shaped filter pad having a plurality of folds to increase its surface filter area, and a foraminous screen element having a marginal flange, the said pad being removably mounted within the said casing by having its edges impingly held between the said seat and 40 the said flange, and the said element being disposed in outer protective relation to the said pad.

NATHAN SCHWARTZ.
